YARN HANDLING MECHANISM

Michael Burgin Emery, Seaford, Del., assignor to E. I. du Pont de Nemours and Company, Wilmington, Del., a corporation of Delaware

Filed Sept. 16, 1964, Ser. No. 396,856

11 Claims. (Cl. 226—97)

This invention relates generally to the field of yarn handling or manipulating devices and, more particularly, to a portable device capable of picking up a running length of yarn and imparting to the yarn, selectively, one of several, widely different, tension levels until the yarn can be transferred to a yarn takup or other winding device.

Frequently, during the handling of yarn lines of either natural or synthetic origin, it is desirable that the yarn be collected temporarily by an auxiliary device rather than by the regular collecting or windup apparatus. In addition, it is often necessary to manipulate the yarn around various elements of yarn processing apparatus such as around draw rolls or through heat treating enclosures. A temporary collecting device is also used when the yarn is cut from winding on a full package and before introducing the yarn to an empty package support and initiating a new windup. Conventional yarn handling devices are described in U.S. Patents 2,667,964 to Miller and 3,094,262 to Ashby et al. This invention is considered to be an improvement over the Miller and Ashby et al. devices.

The primary object of this invention is the provision of portable apparatus which can pick up a moving threadline and impose on that threadline any of several levels of tension which may widely differ for different phases of stringup operations.

A second object is the provision of an apparatus which may be powered solely by pressurized fluid.

A third object is the provision of stringup apparatus that will maintain a high tension level of about 1 to 2 grams per denier (g.p.d.).

Another important object is the provision of apparatus that can simultaneously handle more than one yarn end.

Additional objectives include the provision of apparatus that automatically self-adjusts tension level as yarn ends are added or subtracted; apparatus that is not affected detrimentally by changes in operating speed, temperature or finish and that has reserve tension capability for increased tension demands; and apparatus that is self-stringing and easily operated.

With these and other objects in view, the device for imparting tension to yarn as provided herein includes a housing having a through passage for the yarn. Located within the passage are a fluid jet installation to advance the yarn therethrough under tension and driven roll means, in advance of the jet installation, adapted to engage the yarn to supplement the tension thereon.

Details of two embodiments for carrying out these and other objectives are shown by way of example in the accompanying drawings in which:

FIGURE 1 is a plan view of a preferred embodiment of this invention;

FIGURE 2 is a top plan view of the main body unit 14 of the embodiment shown in FIGURE 1;

FIGURE 3 is a bottom plan view of said main body unit 14;

FIGURE 4 is a cross-sectional view taken on line 4—4 of FIGURE 1;

FIGURE 4a is a continuation of FIGURE 4 showing the extreme right end of unit 14;

FIGURE 4b is a continuation of FIGURE 4 showing the extreme left end of the embodiment of FIGURE 1;

2

FIGURE 5 is a sectional view taken along line 5—5 of FIGURE 6 showing the motors in elevation;

FIGURE 6 is an enlarged sectional view taken along line 6—6 of FIGURE 5.

5 FIGURE 7 is a cross-sectional view taken along line 7—7 of FIGURE 6.

FIGURE 8 shows characteristic curves of air consumption, horsepower and torque versus rotational speed for a typical fluid motor used in this device;

10 FIGURES 9 and 10 show two orientations of the driven rolls with respect to the yarn line in the operation of this device;

FIGURE 11 shows a plan view of a second embodiment of this invention; and

15 FIGURE 12 is a cross-sectional view taken along line 12—12 of FIGURE 11.

In the first embodiment chosen for illustration, the apparatus generally includes a housing 2 having a through passage 4 for yarn 6, a fluid jet installation 8 located

20 within passage 4 adapted to advance the yarn 6 under tension through passage 4, and positively drivable rolls or wheels 10 adapted to engage the yarn 6 to supplement the tension thereon. Preferably, but not necessarily an elongated tube 12 is telescoped within passage 4 to aid 25 in initiating the advance of yarn 6 therethrough.

Referring in more detail to FIGURES 1, 3, 4, 4a and 4b, housing 2 includes two principal parts: a main body unit 14 and a sleeve 16. Unit 14 is connected to sleeve 16 by means of screw threads 18 (FIGURE 4) and is secured by a set screw 20. Sleeve 16 is provided along its central axis with a diffuser 22 which is stepped to form sections of progressively larger internal diameters from right to left. The annular space 23 between diffuser 22 and sleeve 16 serves as a passage for fluid supply to jet 8. At the right end of diffuser 22, within through passage 4, is fluid jet 8 having an inlet tube 24 secured to the interior of sleeve 16 by means of a screw thread 26 which provides positional adjustment of tube 24 with respect to the inner end of diffuser 22. The left end 30 of tube 24 is shaped in the form of a short frustoconical section, part of which fits into the interior of the inner end of diffuser 22 forming an adjustable annulus therewith. Basically, this part of the device is similar to part of the air aspirated yarn handling tool taught by Ashby et al. in U.S. Patent No. 3,094,262. A central hole 28 which is coaxial with diffuser 22 is provided in inlet tube 24. Exhaust tubing 30 is connected to the left end of diffuser 22 and is joined at its discharge end (FIGURE 4b) to a stationary exhaust pipe 32. Pipe 32 dis-

35 charges into a waste box (not shown). Thus main body unit 14, fluid jet 8, diffuser 22, exhaust tubing 30 and exhaust pipe 32 provide an elongated through passage 4 for the yarn 6 to pass through.

40 Exhaust pipe 32 is supported by a housing assembly 34 having a fluid supply port 36 which is connected to a source (not shown) of fluid under high pressure. Though air is preferred, several other conventional fluids may be employed. Connected to housing assembly 34 is a pipe coupling 38 which in turn is connected to flexible tube 40.

45 Tube 40 is joined at its opposite (right) end to sleeve 16 and surrounds exhaust tubing 30 thereby forming an annulus 42. This arrangement permits fluid, entering supply port 36, to flow through annulus 42 into annular space 23 in sleeve 16 and thence to annular chamber 44.

50 When inlet tube 24 is properly adjusted, fluid may flow between inlet tube 24 and the inner end of diffuser 22, down diffuser 22, through tubing 30 and out exhaust 32. This fluid in so flowing creates subatmospheric pressure within central hole 28 in inlet tube 24.

55 At the threaded end of sleeve 16, annular chamber 44 also feeds fluid to radial ports 46 which in turn feed annular space 48 in main body unit 14. Space 48 opens in

to exit 50 which in turn is connected by means of flexible tubing 52 to the inlet of a motor mount 80 to be described below.

Referring still to FIGURE 4 primarily, there is located within main unit 14 a through-going bore 54, defining part of said through passage 4, which is coaxial with screw threads 18 and thus also with sleeve 16. Preferably, slidably mounted in bore 54 is the yarn and secondary air inlet tube 12 which extends outside main unit 14 at its front (right) end where it carries a tip 56 made of an elastomeric material. Tube 12 has through-going bore 58 concentric with its axis.

In an enlarged central portion of main unit 14, there is located a shallow, circular cavity 60, the central axis of which is at right angles to tube 12. In the open side of cavity 60 is located a flat circular plate 62 which is arranged to be manually rotatable in housing 2 by resting on a shoulder machined in housing 2 so that the interface of plate 62 is just clear of the periphery of tube 12. Plate 62 is retained in housing 2 on one side by a curved bar 64 while on the other side it is held by a slideable latch 66 mounted on a stop 68 which is slidably mounted in turn on the outside of tube 12 in a suitable cavity in housing 2. A spring 70 urges the stop 68 and latch 66 to the left. The latch 66 is arranged so that it may be moved manually to the right enough to release plate 62 for maintenance work.

Continuing with FIGURE 4, tube 12 is shown in its extreme inward (or left) position where its inner end is in abutment with an elastomeric seal 72 which is secured to the face of the inlet tube 24. When the tube 12 is situated, as shown, any sub-atmospheric pressure created by fluid flow in the annular orifice between the inlet tube 24 and the diffuser 22 will cause ambient air (called secondary fluid) to flow through the hole in tip 56, through the hole 58 in tube 12, through the hole 28, and thence through the diffuser 22, tube 30 and on through the exhaust pipe 32.

A handle 74 is fixed to tube 12 near its left end. This handle extends outside housing 2 through a slot 76 which is parallel to the axis of tube 12. A short button or pin 78 is attached to tube 12 on the side opposite handle 74. The function of handle 74 and button 78 will be described below.

Details of plate 62 and associated assemblies will now be described by reference to FIGURES 2, 4, 5, 6 and 7. A motor mount 80 is secured to plate 62 by means of flat head screws 82. Within mount 80 are two bores that are parallel to the axis of rotation of plate 62. These bores each accommodate a fluid motor 84. A drilled header 86 in the outer end of motor mount 80 connects to an inlet 88 to which is joined the flexible tubing 52 described above as being connected to exit 50 in housing 2. This system then serves to admit pressurized fluid to the motors 84. As shown in FIGURE 6, the motor shafts extend through plate 62 and each carry low inertia wheels 10. The surfaces of wheels 10 are coated with wear-resistant material such as aluminum oxide. In this particular embodiment the wheels have an outer diameter of 1.67 inches. The motors 84 are of the vane type and are capable of a no-load speed of about 55,000 r.p.m. Motor characteristics are shown in FIGURE 8. Spent fluid from motors 84 emerges from mount 80 through ports 90.

Referring in more detail to FIGURES 6 and 7, the motors 84 shown for illustration are of the type employing radially slideable vanes 92 which are engaged in slots in a rotor 94. The rotor 94 is secured to a shaft 96 which is rotatably mounted in ball bearings 98, said bearings being retained in motor housing 100. Within housing 100 is an eccentric sleeve 102 in surrounding relationship to the outer surfaces of the slideable vanes 92. A port 104 in the upper end of motor 84 admits pressurized fluid from header 86 via passage 106 to space 108 and thence

5

10 through a plurality of ports 110 to a segment of rotor 94. The entrapped fluid expands, causing rotor 94 and shaft 96 to rotate, and "spent" fluid is then ejected from ports 112. The fluid then passes through ports 114 in the wall of motor housing 116 and then into the annular space in motor mount 80 from which it may flow through the ports 90 (FIGURE 5) to the atmosphere.

FIGURE 2 shows, on the inner face of plate 62 and running between wheels 10, a cam track 120 extending across plate 62. Track 120 is straight for about $\frac{2}{3}$ of the distance across a diametrical line, then it curves generally downward and emerges from the edge of the plate near latch 66. Button 78 (FIGURE 4) carried by tube 12, engages track 120 so that, when handle 74 is manually pushed to the right, button 78 follows track 120. For about the first four inches of movement, plate 62 is unaffected but, as button 78 slides through the curved part of track 120, plate 62 is rotated counter-clockwise by about 30° as viewed in FIGURE 2. Further movement of handle 74 causes button 78 to emerge from the extreme (right) end of track 120. Button 78 then comes into abutment with the left face of stop 68. Further movement in this direction of button 78 is possible only against the force of spring 70 acting indirectly through stop 68. Now plate 62 may be rotated manually in either direction and if moved another 10 or 15° in a counter-clockwise direction, button 78 will "fall" into notch 122 in the periphery of plate 62 if handle 74 is released. This mechanism will serve to releasably lock plate 62 in place at about 45° from its starting point. If desired, plate 62 may be manually rotated further in the counter-clockwise direction until button 78 engages notch 124 or notch 126, thus releasably locking plate 62 at either about 100° or 135° respectively from its original starting position, and varying the paths of the running yarn line and the different amounts of yarn wrap around wheels 10. These latter two orientations of plate 62 are illustrated in FIGURES 9 and 10.

exerted on the threadline by the waste jet 8. That is, the jet 8 creates a low tension on the threadline which tends to pull it straight. This tendency creates a normal force of the threadline against the wheel which is dependent on the angle of wrap taken on each wheel. This tension is further regulated by the pull exerted by jet 8. Since the pull of this part of the device varies directly with the size of the threadline being processed, the device is therefore self-regulating in that it keeps approximately the same tension per unit size of yarn even when the size is increased or decreased radically. Thus, a wide variation in tension imposed on a yarn line is made possible by this device and the device is self-regulating with respect to tension variation with the size of the threadline being processed.

As heretofore mentioned, the fluid used herein is preferably air. However, other conventional fluids could also be employed. When using air, the apparatus can operate at normal plant pressures such as 90 pounds per square inch (p.s.i.) and motors 84 are driven by the pressurized air.

When secondary yarn tube 12 is omitted, handle 74 and button 78 are removed, and motors 84 may be manually rotated into position as desired.

An alternate embodiment, considerably simplified though retaining the basic elements of the first embodiment, is shown in FIGURES 11 and 12. This embodiment generally comprises a housing 200 having a through passage 202 for the yarn, a fluid jet installation, formed by inlet tube 206 and diffuser 204 located within passage 202 and adapted to advance the yarn therethrough under tension, and a positively drivable roll or wheel 208 adapted to receive the yarn to supplement the tension thereon. Again, preferably an elongated tube 210 is telescoped within passage 202 to aid in initiating the advance of the yarn therethrough.

Referring in more detail to FIGURES 11 and 12, housing 200 is seen to include a main body unit 212 and a sleeve 214. Sleeve 214 contains jet 206 and hoses and connectors (not shown) which may be identical to those described for the previous embodiment. As shown in FIGURE 12, main body unit 212 is fixed to sleeve 214 by means of threads 216. On main unit 212 there is mounted a fluid motor 218 which is supplied with pressurized fluid from the internal passages of sleeve 214 by connecting tube 220. Again the fluid is preferably air, though other fluids may be employed. Fixed to the shaft of motor 218 is roll or wheel 208. In the embodiment illustrated wheel 208 is 2.36 inches in diameter and is coated with a wear-resistant material.

Yarn inlet tube 210 is slidably mounted in housing 200 in a manner similar to the previous embodiment so that in its innermost location, end guide 222 contacts end guide 224 to connect tube 210 with inlet tube 206 in sleeve 214. A pin 226 is attached to yarn tube 210 to slide it back and forth within passage 202. A slot 228 is provided in housing 200 to accommodate pin 226. A hinged cover 230 (FIGURE 11) is provided on housing 200 for access to wheel 208 during stages of stringup of the yarn handling device. Wheel 208 is within an enlarged section of passage 202, adjacent the yarn, and is substantially coplanar with the yarn. When the tube 210 is slid to the left so that end guide 222 is in advance (to the left) of the enlarged section of passage 202, hinged cover 230 is opened, and the yarn can be pulled around wheel 208 by a suitable threadup hook (not shown) making a full 360° wrap.

In operation, yarn inlet tube 210 is slid to the right thus causing air to be brought in through this tube. A running threadline is then picked up at the other end of tube 210 in the same manner as described for the previous embodiment. Once threaded through the tube 210 and the jet 206 in sleeve 214, the yarn inlet tube 210 would be pushed outward so that the running yarn line would be exposed on operating of the cover 230. The thread-

line would then be seen to be passing out of end guide 222 into end guide 224. With the threadup hook, the yarn line would now be pulled around wheel 208 making the full 360° wrap. Considerable tension increase in threadline would then be created in a manner similar to that described for the first embodiment. Two widely different levels of tension are provided depending on whether or not the threadline is strung around the wheel 208. Alternatively, high and low tension level may be provided by adding a two position valve (not shown) in the supply line 220 to the motor 218. This valve would be used to throttle the fluid during a first stringup phase. When higher tension is required, opening the valve would allow full flow and increased tension level. Adjustable ports (not shown) might be provided in this valve or in the main supply for the entire device to adjust the tension levels to suit various yarn denier levels.

The yarn handling devices described by this invention are extremely valuable in accomplishing stringup through various continuous yarn processing steps. The invention represents an outstanding improvement in yarn handling devices over those disclosed in the art. Of particular significance is the fact that both embodiments are self-regulating with respect to the yarn size since the pull of the positively driven wheels varies directly with the size of the yarn being processed. It is recognized that many modifications of the device may be made by one skilled in the art. Many departures from the preferred embodiments described may be made without departing from the spirit and scope of this invention as defined in the appended claims.

What is claimed is:

1. A device for imparting tension to yarn comprising: a portable closed housing having a through passage for the yarn; a fluid jet installation located within said passage and adapted to advance said yarn therethrough under tension; and independently driven roll means also located in said passage, in advance of said jet installation, said roll means being adapted to engage said yarn and to impart additional tension thereto as it advances through said passage.
2. In a device for imparting tension to yarn of the type which includes a portable closed housing defining a through passage for yarn and a fluid jet installation located within said passage for advancing the yarn therethrough under tension, the improvement which comprises independently driven roll means located within said passage, in advance of said jet installation, said roll means being adapted to engage said yarn and to supplement the tension imparted thereto by said jet installation.

3. The device of claim 2 wherein said passage has an enlarged section in advance of said jet installation to accommodate said driven roll means.

4. The device of claim 2 further comprising means supplying pressurized fluid to said jet installation; and wherein said driven roll means comprises a pair of driven rolls and a fluid motor connected to each roll, said motors being in fluid connection with the means supplying pressurized fluid.

5. A device for imparting tension to yarn comprising: a housing defining an elongated through passage for the yarn, a portion of said passage being enlarged; a fluid jet installation located within said passage, rearward of said enlarged portion, to advance the yarn therethrough under tension; an elongated tube telescoped within said passage, in advance of said jet installation, and adapted to be shifted between a first position in which it is in substantially abutting relationship with said jet installation to aid in initiating the advance of yarn through said passage and a second position in which it is in advance of the enlarged portion of said passage; means for shifting said elongated tube between said first and second position; and driven roll means located within the enlarged portion of said passage and adapted to engage said yarn, when said

tube is in its second position, to impart additional tension thereto as it advances through said passage.

6. A device for imparting tension to yarn comprising: a housing defining an elongated through passage for the yarn, a portion of said passage being enlarged; a fluid jet installation located within said passage, rearward of said enlarged portion, to advance the yarn therethrough under tension; an elongated tube telescoped within said passage, in advance of said jet installation, and adapted to be shifted between a first position in which it is in substantially abutting relationship with said jet installation to aid in initiating the advance of yarn through said passage and a second position in which it is in advance of the enlarged portion of said passage; a plate having an annular periphery mounted within the enlarged portion of said elongated passage and having an axis substantially perpendicular to said passage, said plate being adapted to be rotated within said passage; a cam track extending across said plate, a pair of driven rolls mounted to said plate and adapted to be rotated therewith to engage said yarn, when said tube is in its second position, to impart additional tension thereto as it advances through said passage; a pin member attached to said tube to shift said tube between said first and second positions, said pin member having a button member attached thereto to engage said cam track to thereby rotate said plate and driven rolls whereby when said tube is shifted from its first position to its second position by said pin member, said driven rolls are shifted into engagement with said yarn by said button member; and means driving said driven rolls.

7. Claim 6 further comprising means supplying pressurized fluid to said jet installation and wherein the means driving said driven rolls comprises a fluid motor connected to each roll, said motors being in fluid connection with the means supplying pressurized fluid.

8. Claim 7 further comprising means to releaseably lock said tube in its second position and said rolls in engagement with said yarn, said means comprising notches provided in the periphery of said plate to receive said button member and spring means mounted within said passage in advance of the enlarged portion of said passage to urge said button member into one of said notches.

9. Claim 8, said notches being at predetermined spaced

intervals about said periphery so that said plate and driven rolls may be rotated to impart various levels of additional tension to said yarn.

10. A device for imparting tension to yarn comprising: a housing defining an elongated through passage for the yarn, a portion of said passage being enlarged; a fluid jet installation located within said passage, rearward of said enlarged portion, to advance the yarn therethrough under tension; an elongated tube telescoped within said passage, in advance of said jet installation, and adapted to be shifted between a first position in which it is in substantially abutting relationship with said jet installation to aid in initiating the advance of yarn through said passage and a second position in which it is in advance of the enlarged portion of said passage; means for shifting said elongated tube between said first and second position; a positively driven roll located within the enlarged portion of said passage and having a periphery substantially coplanar with the yarn advancing through said passage, said driven roll adapted, when said tube is in its second position, to have said yarn pass about its periphery as the yarn advances through said passage to impart additional tension thereto; and a fluid motor connected to said driven roll to positively drive it.

11. Claim 10 further comprising means supplying pressurized fluid to said jet; said fluid motor being in fluid connection with the means supplying pressurized fluid.
